[57] **CLAIM**

The ornamental design for a teaching apparatus for
correcting learning problems, as shown and described.

DESCRIPTION

FIG. 1 is a perspective view from the right hand corner
thereof of a teaching apparatus for correcting learning
problems showing my new design;

FIG. 2 is a top view thereof;

FIG. 3 is a front view thereof as viewed along the lines
—3— of FIG. 4;

FIG. 4 is a left side view thereof;

FIG. 5 is a rear view thereof;

FIG. 6 is a right side view thereof; and

FIG. 7 is a bottom view thereof.
